UNITED STATES PATENT OFFICE.

ERICK ERICKSON, OF MINNEAPOLIS, MINNESOTA.

HAND-OPERATED LOADING-MACHINE.

1,360,279.

Specification of Letters Patent. Patented Nov. 30, 1920.

Application filed April 12, 1919. Serial No. 289,673.

To all whom it may concern:

Be it known that I, ERICK ERICKSON, citizen of the United States, residing at Minneapolis, in the county of Hennepin and State 5 of Minnesota, have invented certain new and useful Improvements in Hand-Operated Loading-Machines; and I do hereby declare the following to be a full, clear, and exact description of the invention, such as will 10 enable others skilled in the art to which it appertains to make and use the same.

My invention has for its object to provide a simple and efficient hand-operated loading machine adapted for various uses, but especially adapted for picking up and elevating shocks of hay, bundles of grain and various other things, and placing the same on a rack or wagon. The device is also adapted for the lifting of boxes and the like. The loading 20 machine can be carried on a separate truck or can be applied to the vehicle that is to be loaded. The drawings show the loading machine applied to the rear of a wagon-bed.

Referring to the drawings:—

Figure 1 is a view chiefly in side elevation, but with some parts sectioned, showing the loading machine applied to a wagon as stated;

Fig. 2 is a plan view of the loading machine, some parts being sectioned; and

Fig. 3 is a front elevation of the loading machine with some parts removed.

The numeral 1 indicates as an entirety, the wagon to the rear of which the loading machine is applied. The numeral 2 indicates a vertical mast which is bifurcated at 3, and at its lower end has a vertical stem 4 that is swiveled in a pedestal 5 rigidly secured to the bed of the wagon by bolts 6. The numeral 7 indicates a curved boom or lever which is passed through the bifurcated portion 3 of the mast, and is pivoted thereto at 8. The boom 7 has a handle to swing the same, and the mast, on its vertical pivot 4, 45 and also when the load is not too great, to move the lever to and from the extreme positions indicated by full and dotted lines in Fig. 1.

A pinion 10 is rigidly secured to a drum 50 11 that is free to rotate on a stub shaft 12 projecting from a bracket 13, that is formed as a rigid or integral part of the mast 2. Pinion 10 and drum 11 are held against displacement on stub shaft 12, by pin and washer 14.

A gear 15 meshes with pinion 10 and is

free to rotate on a stub shaft 16, that projects from another bracket 17 that is also integral with the mast 2. Pin and washer 18 hold gear 15 on the stub shaft 16. Gear 60 15 is provided with a hand-crank 15^a, rigidly secured thereto and radiating therefrom. A retaining dog 19 pivoted to the mast 2 operates on gear 15, to hold the boom or lever 8 in a raised position.

The numeral 20 indicates a cable, one end of which is secured to the drum 11 and passes over a sheave 21, which is rigidly mounted to the mast structure 2, but free to rotate, and the other end is secured to the curved 70 boom 7 at 22. The numeral 23 indicates a laterally offset fork-like scoop for the purpose of handling materials such as hay and the like. The said scoop 23 has an upright extended portion 24 which is pivoted to the 75 curved boom 7 at 25. It will be noted that hooks and coöoperating chains may be applied to the pivoted portion 25 of the curved boom 7, thus enabling this form of machine to handle materials such as stone, wheel- 80 barrows and the like.

In picking up a bundle or shock of grain or the like, the boom or lever 7 will be swung with the mast on the vertical pivot 4, so as to shove the teeth of the scoop 23 in the 85 grain. Then the boom will be raised by rotation of the crank 15^a until the load is brought to the proper elevation, and then the fork may be disengaged from the load by giving the boom a backward swinging movement. This device will be found serviceable in many different things, on wagons and 90 vehicles. The term "scoop" is used in a sense broad enough to include either a form of shovel or flat blade. For the loading of 95 hay and the like, the fork will be preferable, but for shoveling up and loading sand, for example, the scoop should be in the form of a shovel.

What I claim is:—

1. In a loading machine of the kind described, the combination with a mast mounted on a vertical swivel, of a boom pivoted to said mast and provided at one end with a hand-piece, and a scoop pivotally suspended 105 from the other end of said boom and projecting in a direction at right angles to the longitudinal axis thereof.

2. In a loading machine of the kind described, the combination with a mast mounted on a vertical swivel, of a boom pivoted to said mast and provided at one end with a 110

hand-piece, and a scoop pivotally suspended from the other end of said boom and projecting in a direction at right angles to the longitudinal axis thereof, a windlass drum 5 mounted on the mast, and a cable attached to said drum, passed over a guide on the upper portion of said mast and attached to the intermediate portion of said boom.

3. In a loading machine of the kind described, the combination with a mast mounted on a vertical swivel, of a boom pivoted to said mast and provided at one end with a hand-piece, a scoop pivotally suspended from the other end of said boom and projecting in a direction at right angles to the longitudinal axis thereof, a windlass drum 15

mounted on the mast, a cable attached to said drum, passed over a guide on the upper portion of said mast and attached to the intermediate portion of said boom, a gear connected to said windlass drum, another gear mounted on the mast and meshing with the first noted gear, an operating crank connected to the second noted gear, and a lock dog on the mast engageable with one of said 20 25 gears.

In testimony whereof I affix my signature in presence of two witnesses.

ERICK ERICKSON.
